UNITED STATES PATENT OFFICE.

ALEXANDER K. SUTHERLAND, OF NEW BRITAIN, CONNECTICUT, ASSIGNOR TO THE TRUMBULL ELECTRIC MFG. CO., OF PLAINVILLE, CONNECTICUT, A CORPORATION OF CONNECTICUT.

QUICK-BREAK SWITCH.

1,288,742.

Specification of Letters Patent. Patented Dec. 24, 1918.

Application filed March 29, 1918. Serial No. 225,448.

To all whom it may concern:

Be it known that I, ALEXANDER K. SUTHERLAND, a subject of the King of England, residing at New Britain, Connecticut, have 5 invented a new and useful Quick-Break Switch, of which the following is a specification.

My present invention relates to what are known as quick break switches, and the objects of the invention primarily are to provide simple and effective means for securing a "quick break" in switches of the "double-throw" type, such as A. C. motor starting switches, reversing switches, and the like.

Special objects of the invention are to prevent the quick break operating means for the switch movement at one side from interfering with the quick break mechanism for 10 the reverse switch movement, and to thus insure a proper quick break action no matter which way the switch is operated.

These objects I have accomplished by the provision of circuit-breaking springs at the 25 opposite sides of the reversely operable switch member, and the provision of a lost motion connection between a switch operating handle and the movable switch element.

Other features of the invention and the 30 details of construction will appear as the specification proceeds.

In the accompanying drawing, I have illustrated the invention employed in a practical commercial form, but would have it understood that changes and modifications 35 may be made without departure from the true spirit and scope of the invention.

In this drawing:

Figure 1 is a front or face view of an enclosed or so-called "safety" type switch having my invention incorporated therein, the switch being shown in the open circuit position.

Fig. 2 is a cross sectional view of the switch taken substantially on the plane of the line 2-2 of Fig. 1.

Fig. 3 is a similar sectional view showing the switch rocked forwardly to establish one 50 set of circuit conditions.

Fig. 4 is another view of this character showing the switch as being rocked in the reverse direction to establish a different set of circuit conditions.

The switch with which I have chosen to

illustrate the invention is of a type now generally used for starting alternating current motors, the movable element of the switch consisting of three parallel switch blades 5 pivotally supported at 6 and arranged when rocked in one direction to make contact with the switch clips 7, and when rocked in the reverse direction to make contact with a set of switch clips 8, these contacts and the circuit arrangements 65 being such as to give the so-called "star-delta" starting and running connections. This switch is mounted in a box or casing 9 and is operated from a handle 10 pivoted in the side wall of the box at 11.

The operating connections from the switch lever to the movable switch element consist in the present disclosure of a rod 12 connected with the hub portion of the handle and having a laterally extending 75 arm 12' overlying the cross bar 13 which connects the switch blades, and working loosely in openings 14 provided in the yoke shaped brackets 15 secured to said cross bar. This, it will be seen, provides a lost motion connection between the switch operating handle and the movable switch element.

The quick break movements are effected in the present illustration by two spiral springs 16, 17 disposed at opposite sides of 85 the movable switch element connected to opposite sides of the cross bar 13 and secured at their opposite ends to suitable abutments such as the brackets 18 secured on the inner wall of the casing, these springs, 90 as will be clear from Figs. 1 and 2, having a "centralizing" effect upon the movable switch element tending to hold it in the intermediate circuit-open position.

When the switch handle is rocked in one 95 direction or the other from the intermediate position shown, one of the quick break springs will be placed under tension and the other spring will be relaxed and either partially or wholly freed from tension, as indicated in Fig. 3. The spring for effecting the quick break of the switch is thus put under tension and the other or idle spring is freed from tension so as not to interfere with the action of the circuit interrupting 100 spring. When, therefore, the handle is operated to open the circuit, after the switch blades have moved far enough for the tension of the quick break spring to overcome the tension of the frictional engagement of 110

the switch clips with the switch blades, said throwing spring will snap the switch blades from engagement with the relatively stationary contacts, the snapping movement of the blades being permitted irrespective of the hold on the handle because of the lost motion connections. This quick break movement obviously will be secured upon the movement of the switch in either direction.

10 A positive quick break is thus assured in a double-throw switch by means of my invention, and furthermore, a force is provided tending to maintain the switch in the intermediate neutral condition. Another 15 effect of the double-throw spring construction is that while a quick opening movement of the movable switch element is effected, this movement is checked by the tensioning of the "relaxed" spring before the 20 movable switch element can move far enough to dangerously approach the opposite set of stationary contacts. This tensioning of the relaxed spring also by checking the movement of the switch element, 25 serves to cushion and prevent shock and jar in the operation of the switch.

I claim:

1. A quick break double-throw switch comprising stationary switch contacts, a 30 pivoted switch member positioned to rock from an intermediate neutral position in opposite directions into engagement with said contacts, a pivoted operating member for swinging said switch member in opposite

directions, a yoke-shaped bracket carried by 35 one of said members and having an opening loosely receiving the other member to thereby provide a lost motion connection between the operating member and pivoted switch member and springs anchored relatively stationary at their outer ends and connected at their inner ends with the movable switch member to thereby normally hold said switch member and through the lost motion connection, the operating member also, in 40 45 the intermediate neutral position.

2. A quick break double-throw switch comprising, stationary switch contacts, pivoted switch blades positioned to rock from an intermediate neutral position in opposite directions into engagement with said contacts, an insulating cross bar connecting the switch blades, a pivoted rocker arm for swinging the switch blades in opposite directions, a yoke-shaped bracket mounted on 50 the cross bar and having an opening loosely receiving the rocker arm to provide a lost motion connection between the rocker arm and pivoted switch blades and springs at 55 opposite sides of the cross bar fastened relatively stationary at their outer ends and connected with the cross bar at their inner ends to thereby normally hold the switch blades and through the lost motion connections, the rocker arm also, in an intermediate 60 65 neutral position.

ALEXANDER K. SUTHERLAND.
